UNITED STATES PATENT OFFICE.

JOSEPH A. SCHIFFERS, OF KNOXVILLE, TENNESSEE.

DYEING COMPOSITION.

1,276,123.

Specification of Letters Patent. Patented Aug. 20, 1918.

No Drawing.

Application filed August 23, 1916. Serial No. 116,442.

To all whom it may concern:

Be it known that I, JOSEPH A. SCHIFFERS, a citizen of the United States, residing at Knoxville, in the county of Knox and State 5 of Tennessee, have invented a new and useful Improvement in Dyeing Compositions, of which the following is a specification.

My improvement relates particularly to the art of dyeing silk and cotton and similar 10 material to any of the light shades which are known as pastel shades, such as flesh color, pink, old rose, baby blue, sky blue, Alice blue, lavender, mauve, green, tan, orange, Nile-green, light green, medium 15 green, and pearl gray.

The object of the invention is to produce a dye in a form and of quality suited to dyeing such materials of said and similar 20 shades conveniently and by persons who are not skilled in the art of dyeing, to the end that said dye may be used in a domestic way for dyeing such articles as hose, silk gloves, ribbons, waists, summer dresses, lace curtains, doilies, and trimmings.

25 My improved dyeing material is in the form of a concentrated mixture which is to be used as hereinafter described.

Said mixture is made as follows:

30 Dye-stuff suitable to the shade which it is desired to produce is selected from the coal-tar dyes which are known under such names as anilin, alizarin, and benzidin dye-stuff.

To one gallon of water add about eight 35 ounces of such dye-stuff and about one quart of anilin oil or monopole oil or any other similar coal tar oil soluble in water and about two ounces of common salt (sodium chlorid). If it is desired to produce soft color 40 tones, also add about half an ounce of chalk (calcium carbonate). The chalk is preferably added in all cases; for its presence is not objectionable, even if it is not desired to produce soft color tones. Thoroughly dissolve or intermingle these several ingredients in the water by agitation and by 45 such heating as may be necessary. The water is preferably boiling when the other ingredients are added.

In this manner the commercial product is 50 prepared. This liquid is then put into and kept in suitable receptacles until portions are to be used for dyeing the materials above mentioned. For the sake of economy, it is

preferable to make the mixture as strong as the ingredients will permit; but all of the 55 soluble ingredients should be dissolved as fully as may be and so remain, in order that whenever any portion of the material is taken from the receptacle, said portion will be in liquid form and fully adapted to making a dilution which will be even throughout. The receptacles are preferably glass bottles holding one or two ounces of the concentrated mixture.

For dyeing any of the fabrics above mentioned, take water, in a clean vessel, in ample quantity to permit immersing the fabrics and moving them about while so immersed. To this water add, drop-by- 60 drop, from the concentrated dye-stuff until the liquor formed by said water and these small quantities of concentrated dye-stuff mixture is of the desired strength. If it is desired to produce light shades, the

quantity of concentrated mixture added to the water to make the dyeing liquor is limited accordingly. If it is desired to produce the darker shades, more of the concentrated mixture is added to form the dyeing 65 liquor. Only a few drops will dye a very

70 pale shade of a desired pastel color. The shade given to the fabric will vary with the length of time the fabric is immersed in the dyeing liquor, the shade becoming darker 75 with the prolongation of the immersion of the material. It is advisable not to use too

much of the concentrated mixture, preference being given to prolonging the period 80 of immersion.

The concentrated dye-stuff mixture is 85 complete in itself, excepting that it does not contain enough water for dyeing the fabrics. Hence no salts or acids are to be added by the person who is to dye the fabrics. Merely water is to be added for the purpose of very 90 much reducing the concentrated mixture. For the purpose of making the concentrated mixture uniform, the bottle is to be well shaken before taking a portion therefrom for making the diluted dyeing liquor.

100 The fabrics to be dyed must be clean and they are preferably made wet with water before they are immersed in the diluted dyeing liquor. Leave the fabric in the liquor until the desired shade has been obtained. Then rinse in one or more clean

water baths. Wring or squeeze out well and hang in a shady place for drying, the fabric being made as smooth as possible.

I claim as my invention,

5 1. In the art of dyeing, the herein-described dye comprising coal tar dye-stuff, common salt, and coal tar oil soluble in water, substantially as described.

2. In the art of dyeing, the herein-described dye comprising coal tar dye-stuff, 10 common salt, and coal tar oil soluble in water and chalk, substantially as described.

In testimony whereof I have signed my name this 22nd day of August, in the year one thousand nine hundred and sixteen.

JOSEPH A. SCHIFFERS.
